(57) **CLAIM**

The ornamental design for a mobile device, as shown and described.

DESCRIPTION

FIG. 1 is a front perspective view of a mobile device showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view thereof, in which a portion of the mobile device is shown in open position;

FIG. 9 is another left-side view thereof; in which a portion of the mobile device is shown in an open position; and,

FIG. 10 is another perspective view of the mobile device.

The broken lines are for illustrative purposes only and form no part of the claimed design.
